COMBUSTION-CHAMBER CONSTRUCTION FOR INTERNAL COMBUSTION ENGINES

Harold M. Jacklin, 1916 N. Meridian St., Indianapolis, Ind.

Original application Oct. 6, 1950, Ser. No. 188,810, now Patent No. 2,805,654, dated Sept. 10, 1957. Divided and this application Sept. 9, 1957, Ser. No. 687,846

3 Claims. (Cl. 123—32)

This invention relates to internal combustion engines, and more particularly to means for controlling the temperature of the combustion space of the engine for the purpose of promoting improved operation especially during starting and warm-up. Among the objects of the invention are to promote prompt heating of the combustion space when the engine is first placed in operation, to avoid overheating of such space as the engine continues to operate, and to provide such temperature control in a simple, effective, and economical manner.

In carrying out the invention, I provide the combustion space or chamber with a liner which, when the engine is cold, has limited or poor contact with its enclosing walls which are cooled in one way or another. When the engine is started, the liner warms up quickly, as its poor contact with the surrounding walls retards the escape of the heat received by the liner from the combustion process. As the temperature of the liner rises, it expands into more effective heat-transmitting contact with the surrounding wall, and the resultant increase in heat transmission to the wall prevents the liner from becoming overheated.

In the accompanying drawings:

Fig. 1 is a section through an engine on the axis of one cylinder;

Fig. 2 is a section on the line 2—2 of Fig. 1; and

Fig. 3 is a fragmental view similar to Fig. 1 but on an enlarged scale illustrating details of the combustion chamber.

The engine shown by way of example in Fig. 1 is of the opposed piston type and, in its entirety, is more fully set forth and described in my prior United States Patent No. 2,805,654, issued September 10, 1957. Such engine comprises a lower block 30 having one or more inlet cylinders 31, an upper block 32 having a corresponding number of exhaust cylinders 33, and a head 34 which is interposed between the two blocks and which is provided with a combustion chamber 35 in line with each pair of inlet and exhaust cylinders. Any appropriate form of means, such as the through-bolts 36, may be used to hold the two blocks and the head in assembled relationship. Each inlet cylinder 31 contains an inlet piston 37 connected by a connecting rod 38 to a crank 39 of a lower crank shaft 40. In a position to be uncovered by the head of the piston 37 as it nears the outer end of its stroke, the cylinder 31 is provided with inlet ports 42 which communicate with an air box 43 and which may be directed tangentially so that the gases entering the cylinder through them will create a circular motion within the cylinder.

Each exhaust cylinder 33 is aligned with and conveniently of the same diameter as an inlet cylinder 31 and contains a reciprocable piston 50 connected through a connecting rod 51 with a crank pin 52 of an upper crank shaft 53, which is operatively connected to the lower crank shaft 40 as through gearing 56. The stroke of

2

the upper piston 50 is considerably less than that of the lower piston, preferably being about one-third to one-half of the stroke of the lower piston. In a position to be uncovered by the piston 50 as it nears the outer end of its stroke, the cylinder 33 is provided with an annular series of exhaust ports 54 the axes of which desirably are inclined outwardly of the cylinder in both radial and axial senses.

The combustion chamber 35 in the head 34 is of smaller diameter than the cylinders 31 and 33 to provide annular shoulders which are closely approached by the pistons 37 and 50 at the inner ends of their strokes. For a purpose which will become apparent hereinafter, the combustion chamber 35 is provided with a sleeve-like liner 61 which, when cold, is of slightly smaller diameter than the opening in the head which receives it. Such liner may be held in place against both axial and rotational movement by radially extending pins 62 which are removably mounted in the head 34 and project into openings in the liner 61.

In the particular engine illustrated in the drawing, which is of the fuel-injection type, the head 34 is provided at each combustion chamber with a fuel-injector 70 adapted to discharge into the associated combustion chamber 35 through an appropriately positioned opening 71 in the liner 61. Desirably, the injector 70 is so oriented that it discharges chordally into the combustion chamber toward an ignition device 72 which is mounted in the block 30 and exposed through an opening 73 in the liner 61.

Fig. 1 illustrates the positions of the pistons 37 and 50 near the inner ends of their strokes a short interval after the occurrence of the explosion. As the pistons are driven outwardly under the influence of the expanding gases, the two crank shafts 40 and 53 rotate in the clockwise direction, as indicated by the arrows in Fig. 1, expansion of the gases continuing until the exhaust piston 50 uncovers the exhaust ports 54. Shortly after the exhaust ports are uncovered, the inlet piston 37 uncovers the inlet ports 42 to admit the new charge. Such charge flows generally upwardly in the cylinders and, forcing the products of combustion ahead of it, produces the necessary scavenging action. As rotation of the crank shafts continues, the exhaust ports close in the inward movement of the exhaust piston 50 and, shortly thereafter, the inlet ports 42 are closed by inward movement of the inlet piston 37. Compression and the next explosion follow.

The upper and lower cylinders and the head 34 are provided with innercommunicating water jackets through which the water or other coolant successively circulates. As shown in the drawing, the water jacket for the lower cylinder is in two sections 80 and 81 lying respectively below and above the inlet ports 42, the two sections 55 being interconnected as by a conduit 83 bridging the ports. The upper cylinder has an axially continuous coolant-receiving space 84 across which exhaust passages 54' extend to connect with exhaust conduits 85. The head 34 (Figs. 1 and 3) has a annular coolant chamber 60 communicating with ports 87 which open into the upper and lower faces of the head in position to communicate with annular grooves 88 and 89 provided respectively in the lower face of the upper cylinder block 32 and in the upper face of the lower cylinder block 30. Ports 90 in the upper cylinder block provide communication between the coolant receiving space 84 and groove 88, while ports 91 provide communication between the upper jacket section 81 of the lower cylinder and the annular groove 89. The ports 87 are angularly disposed from the ports 90 and 91 so that the coolant leaving each port 91 in the lower cylinder block will be

compelled to flow circumferentially for a distance along the groove 89 before entering a lower port 87 of the head. Similarly, coolant leaving each upper port 87 of the head must flow circumferentially for a distance along the groove 88 before entering a port 90 and passing upwardly through the jacket of the upper cylinder. The ports 90 and 91, which are desirably drilled, are equally spaced about the cylinder-axis; and the circumferential flow of liquid in contact with the end faces of the cylinder barrels aids very materially in cooling the inner ends of the cylinder barrels to promote improved lubrication and reduce wear thereat and maintains the head at a lower temperature than would otherwise be possible.

Reference has heretofore been made to the combustion-chamber liner 61 and to its normal loose fit within the head 34. When the engine is first started, the loose fit of the liner 61 within the head 34 retards the transfer of the heat from the liner to the head, with the result that the liner warms up quickly. As liner-temperature increases, the liner expands, the fit between it and the head 34 becomes tighter, and heat transfer from the liner to the head becomes more rapid. Thus, under starting conditions when the engine is cool, the temperature of the liner increases quickly and promotes satisfactory combustion. At the same time, the liner is prevented from becoming overheated as the engine continues in operation, because any tendency to overheat increases the tightness of its fit within the head 34 and thereby increases the rate of heat transfer to the cooled head.

It will be understood that the particular engine shown and described is set forth merely by way of example and that the invention to which this application relates is a loose combustion chamber liner one form of which is shown at 61. The use of such a liner is not limited to opposed-piston engines or to a combustion chamber located in a cylinder or between cylinders. It is only necessary that the liner have, at low temperatures, a relatively loose fit within its enclosing wall to provide poor heat transmission to such wall and that it expand into more effective heat-transmitting contact with the wall when its temperature rises.

This application is a division of my prior application

Serial No. 188,810, filed October 6, 1950, which resulted in my aforesaid patent No. 2,805,654.

I claim as my invention:

1. In an internal combustion engine having a cylinder and a combustion chamber, said combustion chamber having a cooled annular wall, an annular liner for said combustion chamber, said liner having a loose fit in said combustion chamber providing poor heat transmission to the wall thereof at low temperatures but being capable of expanding into firm contact with the chamber-wall under the influence of heat received from burning gases in operation of the engine, said combustion chamber communicating with said cylinder through an opening having a diameter equal at least to the external diameter of said liner whereby any annular gap between the liner and the surrounding wall of the combustion chamber will be in free communication with the cylinder.
2. In an opposed-piston engine having a combustion chamber disposed between two coaxial cylinders, said combustion chamber being of substantially uniform diameter between its openings into said cylinders, an annular liner for said combustion chamber, said liner fitting loosely in said chamber when it and the surrounding chamber wall are at the same temperature but being capable of expanding into firm heat-transmitting contact with such chamber-wall under the influence of heat received from burning gases within the liner, and means located between the ends of said liner for maintaining it in fixed axial position.
3. An engine as set forth in claim 2 with the addition that said means comprises generally radial pins secured in the wall of the combustion chamber and received in openings in said liner.
